UNITED STATES PATENT OFFICE

133,303

DESIGN FOR AN ELECTRIC AIR PURIFIER

Thomas L. Herb, New York, N. Y., assignor to
Sterilseat Corporation, New York, N. Y.

Application January 23, 1942, Serial No. 105,383

Term of patent 7 years

To all whom it may concern:

Be it known that I, Thomas L. Herb, a citizen of the United States, residing at New York, in the county of New York and State of New York, have invented a new, original, and ornamental Design for an Electric Air Purifier, of which the following is a specification, reference being had to the accompanying drawing, forming a part thereof.

In the drawing:

Figure 1 is a perspective view from one side and end of an electric air purifier showing my new design; and Figure 2 is a perspective view showing the other side and end of the purifier.

I claim:

The ornamental design for an electric air purifier substantially as shown.

THOMAS L. HERB.
